UNITED STATES PATENT OFFICE.

GEORGE P. STEWART, OF PALESTINE, TEXAS.

LOCKING DEVICE FOR CAR-COUPINGS.

SPECIFICATION forming part of Letters Patent No. 629,218, dated July 18, 1899.

Application filed May 17, 1899. Serial No. 717,179. (No model.)

To all whom it may concern:

Be it known that I, GEORGE P. STEWART, of Palestine, in the county of Anderson and State of Texas, have invented a new and Improved 5 Locking Device for Car-Couplings, of which the following is a full, clear, and exact description.

This invention relates to means for preventing the accidental uncoupling of car-couplings which have a side-latching knuckle held in closed adjustment by a slideable key.

Car-couplings of the Janney type are subject to accidental release of the knuckle from coupled engagement with a similar coupling 15 by reason of the upward movement of the locking-key that holds the knuckle closed by its contact with the tailpiece of said knuckle. This lifting movement of the locking-key is generally due to the jolting of the cars as 20 they pass over the joints of the rails of the roadway, and the knuckle-tailpiece being slightly rocked by the sway of the cars aids in the improper elevation of the key, that finally is raised above the tailpiece and allows the knuckle to open, thus detaching portions of a train and in some cases causing serious accidents.

The object of my invention is to provide a novel, simple, and practical device which will 30 act automatically and effectually prevent the improper release of the knuckle of a side-latching coupling and which will permit the easy detachment of two cars having couplings provided with the improvement, which 35 may be effected at either side of either car thus coupled.

The invention consists in the novel construction and combination of parts, as is hereinafter described, and indicated in the claims.

Reference is to be had to the accompanying drawings, forming a part of this specification, in which similar characters of reference indicate corresponding parts in all the figures.

Figure 1 is a side view of an end portion of 40 a car and of the improvements applied to a car-coupling thereon. Fig. 2 is an end view of a car-frame, a car-coupling thereon, and the improvements adjusted to hold the knuckle of the car-coupling from release. Fig. 3 45 is a view similar to that shown in Fig. 2, with the exception that the improved key-locking

device is adjusted for a release of the knuckle from the key; and Fig. 4 is a detached perspective view of the gravity block or dog, that is an essential feature of the invention.

55

In the drawings which show the application of my invention the car-coupling A is held projected from the end of a car-body B at the transverse center, as usual, and may have the ordinary or any preferred means for cushioning draft strain, which attachments do not constitute features of the invention and are therefore omitted from the drawings. The car-coupling is of the common side-latching type, generally known as the "Janney" style 60 of car-coupling, and as represented in brief comprises a draw-head A, having the draw-bar A', extended rearwardly therefrom for support beneath the car-frame by a loop-plate A² or any other suitable means.

70

In the forwardly-open chamber a of the draw-head A the L-shaped knuckle A³ is pivoted by the bolt b to adapt the latching member A⁴ thereof to swing laterally and couple with or release another coupling of the same 75 type. The tailpiece A⁵ of the knuckle A³ projects in the ordinary manner into the chamber a of the draw-head and at its inner edge c is adapted for engagement with the vertically-slidable key A⁶.

80

When the key A⁶ is fully depressed, a widened portion d thereon has such contact with the tailpiece A⁵ as will prevent it from rocking in a forward direction, and thus retains the jaw or latching member A⁴ of the 85 knuckle from outward-rocking movement, which would release it from a similar car-coupling.

On the key A⁶ there is the ordinary shoulder e, so formed by diminishing the thickness 90 of the portion of the key below this shoulder that if the knuckle is in nearly-open adjustment said shoulder will, as usual, rest upon the margin of the tailpiece, which will hold the thick portion of the key elevated above 95 the knuckle, and thus permit two car-couplings of this type to be automatically coupled by simply shoving the draw-heads of the car-couplings into contact, it being understood that the knuckles of both car-couplings are in 100 a nearly-opened condition, as just explained.

The description so far as given relates to a

class of car-couplings now in common use and is presented for illustration of the manner in which my improved locking device may be applied to an ordinary side-latching car-coupling, as will now be described.

On an ear 5, that depends from the draw-head A at its left side, the hooked end 6^a of the tripping-lever 6 is loosely secured, preferably by inserting the hook through a perforation of the ear, whereby the lever is disposed transversely below the draw-head in the same vertical plane with the key A⁶. At a suitable distance above the lower end of the key A⁶ the body thereof is reduced, thereby affording a second shoulder g on it, and there is a vertical slot g' formed in the lever 6 at a point which will adapt it to receive the reduced portion of the key that is below the shoulder g. The key is loosely secured in the slot g', preferably by means of the cross-pin h, that is firmly inserted in a transverse perforation of the key-body just below the lever, which adapts said lever to elevate and depress the key when it is correspondingly actuated.

From the right side of the draw-head A depends a furcated ear, affording two parallel spaced flanges i, wherein the upper end of the weighty locking-dog 7 is pivoted by a cross-bolt i'. Preferably the lever 6 is bent to depress the portion of its body that is directly below the dog 7, so that sufficient length may be given to the latter to adapt it for efficient service. To increase the weight of the locking-dog 7 at its lower end, the body thereof is widened, producing thick lateral projections k thereon, so that the weight of the normally-pendent dog will always cause it to assume a vertical plane when free to do so.

On the end of the car-frame B, a proper distance above the draw-head A, a rock-shaft C is supported in a horizontal plane by boxes m, so that said shaft may be rocked when either of two crank-handles C', formed or secured on the ends of said shaft, is manipulated.

An arm C², that extends outwardly from the rock-shaft C above the free end of the lever 6, has the chain 8 or equivalent flexible connection connected by one end to the outer end thereof. From the end of the arm C² the chain 8 depends toward the lever 6 and at a suitable distance therefrom is attached to the bight n of the doubled chain or other flexible connection 9 9^a. The two members 9 9^a of the doubled chain are coupled upon the perforated ears o o', respectively formed upon the lever 6 and the lower end of the dog 7, and it will be seen that as the member 9, that is attached to the lever 6, is slightly longer than the member 9^a of the doubled chain and the latter is more directly in line with the chain 8 a pull upon said chain 8 will commence to rock the dog outwardly in advance of the upward movement of the lever, so that the latter may be lifted and by its upward move-

ment cause the elevation of the pin A⁶ for the release of the knuckle.

It is essential that the weight of the lever 6 and dog 7 be sufficient to insure their instant descent into the respective positions represented in Fig. 2 when the key A⁶ is released from the tailpiece A⁵ of the knuckle, and, as indicated, the fall of the lever aids in causing the quick descent of said key until its head rests upon the draw-head, this of course occurring only when the knuckle is in closed adjustment.

The instant the lever 6 descends the dog 7 falls into a vertical position, which will dispose its weighty lower end above and near to the outer portion of the tripping-lever and adapts said dog to prevent an upward movement of the lever 6 and key A⁶ until the rock-shaft C has been manually rocked to lift the dog away from the lever, as has been explained.

Having thus described my invention, I claim as new and desire to secure by Letters Patent—

1. The combination with a draw-head having a laterally-swinging knuckle, and a vertically-slidable key adapted to hold the knuckle closed when said key is lowered, of a transverse lever held to rock transversely below the key and loosely secured thereto, a rockable dog hung above the lever and holding said lever depressed as well as the key when the lever is lowered, and means to simultaneously rock the dog and lever upwardly for release of the draw-head knuckle.

2. The combination with a draw-head having a side-latching knuckle, a vertically-slidable key, and a transverse lever held loosely by one end so as to dispose the lever below the draw-head and project its free end beyond said draw-head, the key having a loosely-secured engagement at its lower end within a slot of the lever, of a dog hung upon the lower side of the draw-head above the free end portion of the lever so as to prevent said lever from rocking upwardly, a flexible connection extended upwardly from the lower end of the dog and the outer end of the lever, and a rock-shaft supported above the draw-head and adapted to pull upon the flexible connection so as to elevate the dog and lever, when said shaft is rocked.

3. In a locking device for a side-latching car-coupling, the combination with the draw-head, the knuckle, and vertically-slidable key, of a transverse rockable lever loosely secured to the lower part of the key to control its upward movement, a pendent weighty dog on the draw-head and hung above the free end of the lever, and means to simultaneously lift the dog and lever.

GEORGE P. STEWART.
